COUNTING DEVICE

Clarence C. Green, Manheim Township, Lancaster County, Pa., assignor to Armstrong Cork Company, Lancaster, Pa., a corporation of Pennsylvania

Application August 2, 1940, Serial No. 349,602

21 Claims. (Cl. 235—98)

1

This invention relates to counting devices and, more particularly, to a device for counting closures such as crown caps, although the device may be used satisfactorily to count any type of articles moving in single file. My device is particularly adaptable for uses in which a large number of small articles need be counted rapidly and accurately.

Heretofore, in the closure industry, for example, common commercial practice as known to me was to count crown caps by weight; that is, a certain number of caps was supposed to possess a predetermined weight and such caps were packaged by weight rather than by number. Caps are generally sold in gross lots; since the weight of any given number of caps varies slightly due to slight variations in liner thickness, liner density, metal thickness, and the like, it was necessary to include more than the required number of closures in each package to ensure that the required number of caps was present in each package. Even though crown caps are inexpensive, it will be appreciated that when millions of caps are packaged yearly a slight overrun for each individual package involves tremendous additional expense. In addition, many states use what are generally termed "tax-paid crowns" as a means of indicating revenue taxes have been paid on malt beverages. Since it is impossible to determine by weight the exact number of caps in a package, it will be understood many difficulties arise in the packaging of such articles; if more than the precise number of crowns are packaged, revenue crowns are issued on which tax has not been paid while if less than the exact number of caps is packaged in a container, greater taxes are paid by the customer than is necessary and this is a frequent source of complaints by customers.

These additional expenses were deemed necessary, however, since no precise device was available which would function satisfactorily in counting caps without decreasing the speed of the manufacturing operations. Since a cap per se is so inexpensive all operations in connection with the manufacture of caps must be conducted at high speed in order to be economically practicable. To obviate decrease in the speed of the manufacturing operations, it is essential that the counting device be capable of counting caps at at least a rate of 800 caps per minute for extended periods and be capable of counting accurately a peak load of approximately 2200 per minute.

The chief object of my invention is to provide

2

a rapid and accurate counting device which is economical in manufacture and inexpensive in operation. An object of my invention is to provide a device capable of disposing articles in single file and passing them past a counting mechanism. A further object is to provide a counting device capable of segregating articles in predetermined amounts. A still further object is to provide an automatically operating counting mechanism for use with closure manufacturing and packaging devices which is efficient, rapid, and accurate in operation. A still further object is to provide means for aligning closures in single file to enable them to be counted as they pass through a predetermined location. A still further object is to provide means for carrying closures to a predetermined location where they are counted and for removing the closures therefrom.

This invention relates to a counting device which comprises in combination means for disposing articles to be counted in single file, a conveyor for carrying the articles through a predetermined zone in which they are counted, and counting means adapted to be actuated by the forward movement of the articles to be counted. More specifically, haphazardly disposed closures are separated and placed in single file by centrifugal force and are then continuously and progressively carried past a trigger or finger which is engaged by each closure of the file and serves to actuate the counting mechanism. The counting mechanism counts each closure and likewise adds the number of closures counted. The closures are then automatically separated in predetermined lots as determined by the counting mechanism and packaged.

The attached drawings illustrate a preferred embodiment of my invention, in which

Figure 13 is a view in elevation of the clutch plate.

Referring to the drawings, the foundation of the device consists of the plate 2 connected by a hollow column 4 to a table 6. The foundation is supported by three casters 8 or three legs 10 disposed at spaced points around the periphery of the plate 2, as hereinafter described. The feeding and separating mechanism is carried by the table 6 and is adapted to receive caps and convey them in single file to a conveyor which carries them through a counting zone in which they are counted. The feeding and separating mechanism comprises (Figure 2) a turntable 12 mounted on the end of a shaft 14 connected to the reduction unit 16 of a motor 18 seated upon the table 6 and bolted thereto. The turntable 12 is actuated by the motor 18 at any suitable speed, it being essential that the turntable 12 be actuated at a rate of speed sufficiently great that centrifugal force maintains caps disposed thereon adjacent its periphery. Preferably, turntable 12 is provided with a plurality of openings therein (not shown) to permit extraneous foreign matter such as dirt and liner particles to fall through the openings into a suitable receptacle rather than permitting such particles to remain on the table or to permit them to be carried to the containers in which the caps are packed for shipment.

A cone-shaped disk or plate 20 is placed centrally of the turntable 12 and is bolted thereto so that it rotates at the same speed as the turntable. The turntable 12 and the cone-shaped disk 20 are rotated in the direction of the arrows (Fig. 2). Extending peripherally of the table 12 is a guard 22 supported by brackets 24 bolted to the table 6. The guard 22 serves to prevent caps being separated and disposed in single file from being thrown from the table 12 by centrifugal force and likewise serves as a retaining wall against which the caps may be placed in single file. A cover 26 is placed above a portion of the periphery of the table 12 and is spaced from the table 12 a distance sufficient to permit single caps to pass thereunder as the turntable rotates. The shape of the cover 26 is shown in Figure 2 and it is supported by the guard 22 in fixed position. If, for example, several caps are piled on top of one another as they are carried by the table 12, the guard 26 permits the lower cap only to pass thereunder and prevents the upper cap or caps from passing thereunder. The turntable 12 in combination with the guard 22 thus passes a single layer of caps to a conveyor hereinafter described along which the caps are counted.

The cover 26 ensures that only a single layer of caps passes thereunder to be carried to the

conveyor. It is desirable, however, that the caps be arranged in single file, and preferably in substantial alignment, to permit precise operation of the counting mechanism, hereafter described.

5 In some cases, a cap 30 (see Figure 2) may wedge between two other caps 30' and 30" and thus prevent a single file or line of caps from passing upon the conveyor and jamming or closing the entrance thereto. To obviate jamming at the entrance to the cap conveyor, I provide an agitator 32 positioned adjacent the cover 26 and at substantially the entrance thereto. The agitator 32 may be a hexagonal rod and is supported by a motor 34 secured by brackets 36 to the guard 22. The agitator 32 is rotated by the motor 34 at a high rate of speed in a direction opposite to the direction of rotation of the turntable 12. As improperly disposed caps are carried to the entrance to the conveyor, they strike the rapidly 10 rotating agitator 32 and are thus hurled inwardly toward the cone-shaped disk 20. Centrifugal force again hurls the caps outwardly upon the table 12 which carries them when properly placed thereon to the cap conveyor which 15 carries them past the counting mechanism.

20 A brief description of the operation of the feeding and separating mechanism may be desirable to aid in a full comprehension of its operation. A plurality of caps, shown in dotted outline in Figure 2, are fed or dropped from a 25 hopper or a belt (not shown) upon the cone-shaped disk 20. Since the disk 20 is rotating rapidly in a counterclockwise direction, such caps are hurled outwardly upon the turntable 20 by centrifugal force until their outward movement is halted by the guard 22 which retains 30 them at the periphery of the table 12. The table 12, rotating rapidly, carries the caps forwardly under the cover 26 which prevents more 35 than a single layer of caps being carried thereunder. The agitator 32, placed adjacent the cover 26 and substantially at the entrance to the conveyor, ensures that only a single line 40 of caps passes upon the conveyor by removing caps not disposed adjacent the periphery and 45 forces caps adjacent the periphery in alignment. Thus the caps are fed upon the conveyor.

The conveyor 38 (Figures 1, 2 and 3) which 50 receives the caps fed from the turntable 12 in single file and in substantial alignment carries the caps through a counting zone. A second conveyor 40 is provided placed above the conveyor 38 which holds the caps securely in position 55 thereon as they pass through the counting zone. The conveyors 38 and 40 preferably consist of endless belts provided with a soft, resilient, frictional facing of rubber or similar frictional material which will securely hold the caps in proper position without marring the decoration of the 60 caps.

65 Belt conveyor 40 passes around pulleys 42 and 44 keyed to shafts 46 and 48 journaled in plates composing a portion of the framework of the device. The belt 40 may be tightened as desired by moving the plates in which the shafts 46 and 48 are journaled away from one another and holding them in fixed position by means of the set screw 50. The pulley 44 is driven by means of a sprocket wheel 52 keyed to shaft 43 and connected by a chain 54 to a sprocket wheel 56 mounted on a shaft 58 connected by a suitable bearing box 60, supported by a housing 62 bolted to the table 6, to a bevel gear 64 meshing with a bevel gear 66 mounted on the shaft 14 of the motor 18. The belt 40 is driven at a pre- 70 75

determined speed, through the connecting gear and chain, by the motor 18.

Belt conveyor 38 passes around pulleys 68, 70, and 72 mounted on shafts 74, 76, and 78 journalled in plates forming framework of the device and may be tightened similarly to belt 40 by means of the set screw 80. Shaft 76 supports a spur gear 82 keyed thereto which meshes with a similar gear 84 keyed to shaft 48. The belt conveyor 38 is thus driven by the same means as belt 40 and at the same speed. The belts 38 and 40 are spaced apart a distance sufficient to permit a single line of caps to enter therebetween and are so arranged as to securely hold such caps therebetween while passing them through the zone in which they are counted. The caps need be held sufficiently securely between the belts 38 and 40 as to permit them to force outwardly a trigger or finger connected to the counting mechanism during their forward movement. If desired, a guide (not shown) may be disposed between or adjacent the belt conveyors 38 and 40 to afford additional assurance that each cap being carried forward by the conveyors strikes or forces outwardly the trigger connected to the counting mechanism.

The counting mechanism is mounted on a table 86 supported by the columns 88 resting on the table 6, and is enclosed in a case 90 although such case is removed in Figures 1 and 4 to illustrate the counting mechanism. The dial wheels 92 and 94 are supported by a shaft 96 journalled in brackets 98 and 100 bolted to the table 86. A torque motor 102 bolted to the framework of the device serves by means of a pinion 104 and a bevel gear 106 to rotate the shaft 96. It will be understood, of course, suitable spring mechanism may be used in place of the torque motor 102. The dial wheels 92 and 94 are supported by the shaft 96, but they are not keyed or pinned thereto and are not rotated directly thereby but are driven by suitable mechanism as hereinafter described.

Referring now primarily to Figures 4, 5, and 6, there is shown an escapement which prevents the shaft 96 from rotating. The escapement comprises a scape wheel 112 keyed to a shaft 114 journalled in the bracket 116 and the bracket 98, the bracket 116 being bolted to the table 86, and a pallet 118, supported by a bracket 120, in engagement with the scape wheel 112 and pivoted at the point 122 (see Figure 6) of the bracket 120. The pallet 118 has an arm 124 for a purpose herein-after described. A spur gear 126 is keyed to shaft 114 and meshes with a spur gear 128 keyed and pinned to the shaft 96.

A ratchet wheel 130 is keyed and pinned to the shaft 96 so that it rotates therewith. A spring detent 132 is bolted to the inner surface of dial wheel 92 and engages or fits between the teeth of ratchet wheel 130. Thus when ratchet wheel 130 rotates, dial wheel 92 rotates therewith since it is connected thereto by the spring detent 132. Dial wheel 92 may be rotated in either direction by hand, if desired, to set it at any desired point without rotating ratchet wheel 130 since the detent 132 is made of spring metal which permits it to be sprung over the teeth of the ratchet wheel. Dial wheel 92 counts individual articles and since it is desired to count in gross lots, it is divided in 144 sections. Since it is actuated by the ratchet wheel 130, it is necessary that the ratchet 130 be provided with 144 teeth; one for each article indicated on dial wheel 92.

Before continuing the description of the dial wheel rotating mechanism, I will explain the tripping mechanism in order to describe how an

individual cap is counted. Referring to Figures 1, 2, and 3, a flexible spring metal trigger or finger 134 is provided which in normal position extends between the belts 38 and 40. Trigger 134 is pinned to a lever 136 (see Figures 1 and 3) supported by a bracket 138. The upper end of the lever 136 is provided with left-hand threads and is screwed within an arm 140. The arm 140 is pinned to a clevis 142 which is attached to a trip rod 144. Rod 144 (see Figure 6) passes through a stop 146 and is threaded to a clevis 148 to which is pinned the arm 124 of the pallet 118. A helical spring 150 surrounds the rod 144 and is held between the stop 146 and the clevis 148.

When the trigger 134 is engaged by a cap, see Figures 2 and 3, it is pushed or forced outwardly, rotating the lever 136 and the arm 140, thus pulling the rod 144 outwardly—to the left as shown in Figure 3 and to the right as shown in Figure 6—thus rotating the pallet 118 and compressing the spring 150 between the stop 146 and the clevis 148. As the pallet 118 pivots about the point 122, it releases the scape wheel 112 and permits it to move forward the distance of a tooth thereof and as it returns to normal position the wheel 112 is again permitted to move forward by the release of a second tooth; the release of wheel 112 by pallet 118 permits torque motor 102 to rotate shaft 96. The rotation of the shaft 96 rotates the ratchet wheel 130 a predetermined distance and thus the dial wheel 92, connected to the ratchet by spring 132, rotates a distance of one section from a zero point, indicating that one cap has passed the trigger 134.

After the cap has moved forward past the trigger 134, the trigger 134 is released and is urged inwardly to normal position by attempted expansion of spring 150 which moves the rod inwardly, pivoting the pallet 118 in the opposite direction so that a tooth thereof engages the teeth of the scape wheel 112 and prevents its rotation which prevents the rotation of shaft 96 and the ratchet wheel 130. The same procedure is repeated for each individual cap.

Since caps are generally sold in gross lots it is desirable that suitable means be provided for counting or adding caps in gross lots as well as individually and for this purpose the dial wheel 94 is provided. The dial 94 is divided in two portions, each portion covering one-half of the wheel; each portion is subdivided into fifty sections denoting one gross each and each portion of the dial is capable of counting to fifty gross. I will now describe the manner in which it is actuated.

Referring to Figures 5 and 7, there is shown a cam 152 supported by the shaft 96 and bolted to the dial wheel 92 so that it rotates with the dial 92. The cam 152 is not pinned or keyed to the shaft 96 so that it does not rotate therewith but is driven by the dial wheel 92. A ratchet wheel 154 is placed adjacent the cam 152 and is bolted to the dial wheel 94. A lever 156 is pivoted on a bracket 158 with its tooth 160 in engagement with the cam 152. The lever 156 is held in engagement with the cam 152 by means of a helical spring 161 stretched between the lever 156 and a bracket 162 bolted to the table 86. A pawl 164 is pivoted on the lever 156 and is held in engagement with the ratchet wheel 154 by a helical spring 166 stretched between an end of the pawl 164 and the foot 168 of the lever 156. A second pawl 170 is pivoted on the bracket 162 and is held in engagement with the ratchet wheel 154 by means of a spring 172 stretched between the end of the pawl and a

flange 174 integral with the bracket 162. The pawl 170 serves to prevent movement of the ratchet wheel in one direction but is so designed as to permit its rotation in the opposite direction; the end of the pawl sliding harmlessly over the teeth of the ratchet as it is rotated in one direction but engaging such teeth and preventing rotation in the opposite direction. Dial wheel 94 may, of course, be set in any desired position by rotation manually.

The cam 152 is rotated by the dial wheel 92. As it rotates, it gradually moves the lever 156 outwardly (toward the left in Figure 7). The lever 156 is pivoted at 176 and as it moves outwardly, it pivots the pawl 164 at the point 178; as the tooth 160 of the lever 156 reaches the high point of the cam 152 and drops off, the pawl 164 is urged into firm engagement with and acts to rotate the ratchet 154, thus turning the dial 94 one-hundredth of a revolution, to indicate 144 individual caps or 1 gross of caps has passed the trigger 134. It will be understood that the lever 156 in moving outwardly stretches the spring 161 so that immediately the high point of the cam 152 has passed, the spring will immediately urge it against the cam, which, of course, returns the pawl 164 to its original position. The pawl 170, as stated above, prevents positively any backward rotation of the ratchet and likewise, of course any backward rotation of the dial 94.

The belt conveyors 38 and 40 carry the caps forward past the trigger 134 and to a chute 180, shown in Figures 1 and 2, down which the caps slide to the containers in which they are packaged for shipment. The chute 180 is mounted on the bracket 181 secured to the framework of the device. The chute 180 includes a base 182, side plates 184 and a V-shaped plate 186 which divides the lower portion of the chute in two sections. As discussed above, it is desirable that the caps be segregated or separated in predetermined lots for shipment so that only a predetermined number of caps be placed in individual packages. Accordingly, I provide a gate 188 which may be oscillated to direct the caps fed to the chute 180 into either of the two sections in which the lower portion of the chute is divided. Caps may be placed in a container and when the required number of caps is placed therein, the gate 188 may be actuated to direct the caps in the second chute section from which they may fall into a second container and the procedure repeated throughout the operation.

The gate 188 is mounted on shaft 190 secured by means of the bushing 192 and the lever 194 to the plunger 196 of solenoids 198 connected to the contacts 200. Referring now to Figures 5 and 8, the contacts 200 are mounted on a bracket 202 bolted to the switch base 204. Contacts 206 are secured to springs 208 bolted to the switch base 204. Pins 210 serve to connect the springs 208 and contacts 206 carried thereby to levers 212 and 212', pivoted on the switch base 204. The levers 212 and 212' engage and serve as cam followers for a cam 214 disposed over bushing 110 and mounted on the hub of ratchet 154 so that it rotates therewith. The levers 212 and 212' are securely held in engagement with the cam 214 by means of a helical spring 216 stretched therebetween.

As stated above, the cam 214 rotates with the ratchet 154. As the cam 214 rotates, the levers 212 and 212' follow its surface and close and open the contacts. As shown in Figure 8, lever 212' has passed a high point of the cam and has

rotated about its pivot thus moving the contact 206 inwardly so that it engages contact 200 closing the circuit to energize the solenoid 198 to move plunger 196 to rotate the gate 188 to the position shown in Figure 2. As the cam 214 continues its rotation, lever 212' moves outwardly thus breaking the circuit. The gate 188 is retained in the position to which it has been rotated. Lever 212 follows the cam contour and as it drops off the high point of the cam closes its accompanying contacts 200 and 206 to energize the other solenoid 198 to move plunger 196 in the opposite direction thus rotating or swinging the gate to the position shown in dotted outline in Figure 2. The cam surface is so designed that the gate 188 is rotated or swung in each direction for each complete revolution of the ratchet 154. Thus, as the counting mechanism indicates fifty gross, the gate is swung or rotated, directing the oncoming caps into the second chute section and into a second container. The procedure of course is repeated as counting of the caps continues. It will be appreciated the cam surface may be so designed as to permit the gate to be rotated or swung back and forth for any predetermined number of caps and my invention is not to be construed as limited to any particular lot of caps. Obviously, in other uses or in the same use, smaller or larger numbers of articles may be packaged in containers, and the mechanism designed accordingly.

I will now describe the operation of my device by following a cap through the various steps it undergoes during the procedure of counting and separating a number of caps into predetermined lots. Referring to Figures 1 and 2, a plurality of caps are dropped from a belt or hopper on the cone-shaped disk 20 whence they are flung outwardly by centrifugal force until outward movement is stopped by the guard 22. They are then, of course, disposed on the turntable 12, which is rotating rapidly, and which carries them to the belt conveyor 38. The cover 26 and the rapidly rotating agitator 32 ensure that a single layer of closures in single file are transferred to the belt conveyor 38. The caps are held securely between the conveyor 38 and a second belt conveyor 40 and passed within the counting zone in which is disposed the trigger or finger 134 of the counting mechanism.

Each cap as it passes through the counting zone strikes the trigger or finger 134 and forces or urges it outwardly thereby pulling the rod 144 outwardly or to the left, as shown in Figure 3. Movement of the rod in this direction, refer to Figure 6, rotates the pallet 118 about its pivot 122 thus releasing the scape wheel and rotating the shaft 96 a predetermined distance by means of the torque motor 102 and the rotation of the scape wheel. Since the ratchet 130 is keyed and pinned to the shaft 96 it rotates therewith. The detent 132 of the individual dial wheel 92 is in engagement with the teeth of the ratchet 130 and, as the ratchet 130 rotates, the dial wheel 92 rotates a predetermined distance to indicate one cap has been counted. As the cap passes the trigger 134, it, of course, returns to its normal position ready for contact with a second cap.

Since it is desirable that caps, for example, be added or counted in predetermined lots as well as counted individually, the dial wheel 94 is provided. Dial wheel 94 is adapted to count caps in gross lots. The dial wheel 94 is secured to the ratchet 154 and is actuated by the cam 152 which is secured to the individual dial wheel 92. The

cam 152 rotates with the dial wheel 92. The lever or cam follower 156 rides on the cam; the pawl 164 is pivoted on the lever 156 and is held in engagement with the ratchet 154 (see Figure 7). As the cam 152 rotates it forces the lever 156 outwardly, pivoting the pawl 164 and enabling it to rotate the ratchet a predetermined distance. Each revolution of the cam 152, through the lever 156 and pawl 164, thus turns the ratchet 154 a predetermined distance. Since 144 caps need be counted to complete a revolution of the cam 152, such predetermined distance rotated by the ratchet 154 rotates the dial 94 to indicate one gross of caps has passed the trigger 134. Backward movement of the ratchet 154, which would rotate the dial 94 backwardly, is prevented by the pawl 170, as described above.

The caps after they pass the trigger 134 are carried by the conveyors 38 and 40 to a chute 180 down which they slide in containers to be packaged. I have stated that it is desirable that the caps be segregated in predetermined lots and for this purpose a gate 188 is provided in the chute which serves to direct the caps in one of the two chute sections provided. The gate 188 is controlled from the ratchet 154 by means of the cam 214 secured thereto. The surface of the cam 214 is so designed as to actuate the gate for each half revolution of the ratchet 154—each fifty gross as indicated by dial wheel 94. The levers 212 and 212' ride on the cam surface and as they are moved inwardly and outwardly they alternately energize the solenoids which actuate the gate 188. The gate 188 thus divides caps counted individually and by gross lots in predetermined lots of fifty gross each.

It is desirable that some check be maintained on the total production for a day. For this purpose, I provide a revolution counter 220 connected by a bevel gear 222 to the pinion 104 mounted on the shaft of the torque motor 102. As designed, each revolution of the motor 102 counts one gross on the counter 220. Since this counter forms no part of my invention, it is not believed a lengthy description thereof is necessary.

As disclosed in Figure 1, my device may be supported on casters 8 or legs 10. For ease in moving the device, the casters are provided while it may be positioned on its legs 10 during operation thereof. A simple lever mechanism is provided for this purpose and by pivoting the levers on fulcrums, the device may be positioned on its legs 10 while when it is desired to move the device, the levers are returned to their first position and the device again positioned on its casters 8.

In Figures 9-13 inclusive, I have illustrated a modified form of my invention in which a third dial wheel is provided adapted to count caps in lots larger than fifty gross and, preferably, in lots of one hundred and two hundred gross. Suitable mechanism is provided to connect this dial wheel with the individual dial wheel 92 and likewise to disconnect the fifty gross wheel from the individual dial wheel. Such mechanism is hereafter described in detail.

Referring primarily to Figures 9 and 10, there is shown the individual dial wheel 92 which is actuated similarly to the individual dial wheel previously described by means of the rod 144 and the escapement mechanism 112 and 118. The fifty gross dial wheel 94 is likewise actuated similarly and it is believed a detailed description of the actuation of such wheels is not necessary. A third dial wheel 300 is provided mounted on a

bushing 302 on the shaft 96. This wheel 300 carries two scales each of which is divided into two hundred portions. One scale counts articles in two-hundred gross lots and is numbered from 1-200; the other scale counts articles in one-hundred gross lots and the scale is divided in two sections each counting from 1-100 gross. It will be appreciated the wheel 300 is rotated a certain distance in counting one gross of articles regardless of which scale is being used to indicate the number of articles counted. The dial wheel 300 is actuated by means of a ratchet 304 and is connected thereto by the detent 306. A spur gear 308 is secured on the bushing 302 and is connected to the ratchet 304 which is also secured to bushing 302. The spur gear 308 is driven by a suitable train of gears designated generally at 310 connected to a spur gear 312 mounted on a shaft 314. On the opposite end of the shaft 314 is mounted a gear 316 connected by a suitable train of gears designated generally at 318 to a gear 320 connected to the cam 152 secured to the individual counting wheel 92. Thus the dial wheel 300 is driven from cam 152 secured to the individual wheel 92.

A clutch is provided to disengage the fifty gross counting wheel 94 if desired. By "disengage" I mean to release it from effective operation. This clutch consists of a detent plate 322 suitably marked to indicate the various scales of the dial wheels, and a rod 324 passing therethrough on which is placed a handle 326 in engagement with the plate 322 and adapted to be rotated to indicate on which dial wheel, and if it be wheel 300, on which scale caps are being counted. At the opposite end of the rod 324 is placed a yoke 328 which serves to move cams 330 and 330' slidably attached to the shaft 314. As the handle 326 is rotated, it turns the rod 324 so that the yoke 328 slides cams 330 and 330' on the shaft 314. As shown in Figure 11, cams 330 and 330' are formed with different configurations so that cam 330 is provided with two high points whereas cam 330' has only a single high point. Cam 330 through the intervening mechanism oscillates the gate each time a hundred gross of articles have passed the trigger 134 while cam 330' oscillates the gate through the intervening mechanism when two-hundred gross of articles have passed the trigger 134. Needless to say, the two cams are not in use simultaneously but either is used dependent upon whether it is desired to separate the articles in lots of one hundred or two hundred gross.

The wheel 94 is actuated from the cam 152 by means of the lever 156 and the pawl 164, as previously described. Lever 156, see Figure 11, carries an arm 332 adapted to follow the surfaces of cams 330 and 330'. Thus, so long as the clutch is in neutral position, the wheel 94 is actuated in the manner above described and plate 322 indicates that gross counting is being conducted on wheel 94. When the handle 326 is moved to one of the positions in which the wheel 300 is actuated to count in gross lots, either 100 or 200 gross, rotation of the rod 324 forces the yoke 328 to slide either of the cams 330 or 330' in engagement with the arm 332. As the cam, either 330 or 330', with which the arm is in engagement rotates, it raises the arm 332, forcing the lever outwardly so that the pawl 164 which actuates the ratchet 154 is actuated from either the cam 330 or 330' rather than the cam 152. Since the gate actuating mechanism is driven from the

ratchet 154, it is suitably actuated to separate caps in predetermined lots.

For clarity of understanding, I will describe the operation of the mechanism. Let us assume it is desired to count caps in lots of one hundred gross each. The clutch handle 326 is moved to the position indicating one hundred gross on the clutch plate 322, which rotates rod 324 and actuates the yoke 328 to slide cam 330 in engagement with the arm 332. The cam is disposed on and rotates with shaft 314 which is rotated by the gear 320, gear train 318, and gear 316, and as the cam rotates it raises arm 332 thus moving lever 156 outwardly. As lever 156 drops from the high points of cam 330, it permits pawl 164 15 to actuate ratchet 154. By means of the gear 312, gear train 310 and gear 308 the wheel 300 is actuated. Since cam 214 rotates with ratchet 154, the switching mechanism is actuated to swing the gate to separate caps in predetermined lots.

The advantages of my device are obvious. Any number of articles may be counted, added and segregated into lots of predetermined size. My device is especially adapted for high speed operations. It functions rapidly and accurately, is 25 economical in cost and is entirely automatic in operation. It is of especial desirability in the accurate and rapid packaging required for small articles such as closures and eliminates the inherent inaccuracies present in the means here- 30 tofore used for such purposes.

While I have described and illustrated a preferred embodiment of my invention it will be understood my invention is not so limited since it may be otherwise embodied or practiced within 35 the scope of the following claims.

I claim:

1. In a machine for counting articles, the combination with means for conveying articles in single file through a counting zone, of a trigger disposed in said zone adapted to be actuated by movement of articles therethrough, a rod connecting said trigger to the pallet of an escapement, a dial wheel for indicating the number of individual articles passing through said zone, means for rotating said dial wheel, rotation of said wheel being prevented by said escapement, movement of said trigger pivoting said pallet to release the scape wheel thus permitting rotation of said dial wheel, a second dial wheel for registering and visibly indicating multiples of the individual count, a ratchet connected to said second dial wheel, a cam connected to and mounted for rotation with said first-mentioned dial wheel, a lever held in engagement with said cam, and a pawl secured to said lever and adapted to rotate said ratchet thereby rotating said second dial wheel a predetermined distance; means for segregating counted articles in lots of predetermined size, and means operable with said ratchet for actuating said segregating means.

2. In a machine for counting articles, the combination with means for conveying articles in single file through a counting zone, of a trigger disposed in said zone adapted to be actuated by movement of articles therethrough, a dial wheel for indicating the number of individual articles of a predetermined lot which have passed through the counting zone, means for rotating said dial wheel, an escapement serving to prevent rotation of said dial wheel, actuation of said trigger releasing the escapement thereby permitting rotation of said dial wheel, a second dial wheel for registering multiples of the individual count, a cam connected to said first mentioned dial 75

wheel, a ratchet connected to said second dial wheel, a lever engaging the surface of said cam, and a pawl secured to said lever and adapted to rotate said ratchet thereby rotating said second dial wheel a predetermined distance.

3. In a machine for counting articles, the combination with means for conveying articles in single file through a counting zone, of a trigger disposed in said zone adapted to be actuated by movement of articles therethrough, a rod connecting said trigger to the pallet of an escapement, a dial wheel for indicating the number of individual articles of a predetermined lot which have passed through the counting zone, means for rotating said dial wheel, rotation of said wheel being prevented by said escapement, movement of said trigger pivoting said pallet to release the scape wheel of the escapement thus permitting rotation of said dial wheel a predetermined distance to indicate an article has passed through the counting zone, a second dial wheel for registering multiples of the individual count, a ratchet connected to said second dial wheel, a cam connected to and mounted for rotation with said first mentioned dial wheel, a lever held in engagement with said cam, and a pawl secured to said lever and adapted to rotate said ratchet thereby rotating said second dial wheel a predetermined distance.

4. In counting mechanism, the combination of a rotatable dial wheel for indicating the number of individual articles which have passed through a counting zone, a ratchet to operate the same, means for separating counted articles in lots of various sizes, a plurality of cams operable with said ratchet, a lever carrying a pawl adapted to actuate a second ratchet, means for selectively connecting any of said cams to said lever in actuating relationship dependent upon the size of the lot desired, and means connected to said second ratchet for actuating the separating means.

5. In counting mechanism, the combination of a rotatable dial wheel for indicating the number of individual articles which have passed through a counting zone, a ratchet to operate the same, means for separating counted articles in lots of various sizes, a second rotatable dial wheel for registering multiples of the individual count, a gear train operable with said ratchet, a shaft, said gear train being connected to said shaft, a second gear train, a second ratchet, said second gear train connecting said shaft and said second ratchet, means connecting said second ratchet to said second dial wheel, and a plurality of cams slidably attached to said shaft and operable with said first-mentioned ratchet, each cam being operable selectively to actuate the separating means thus separating counted articles in lots of predetermined size.

6. In counting mechanism, the combination of a rotatable dial wheel for indicating the number of individual articles which have passed through a counting zone, a ratchet to operate the same, means for separating counted articles in lots of various sizes, a second rotatable dial wheel for registering multiples of the individual count, a gear train operable with said ratchet, a shaft, said gear train being connected to said shaft, a second gear train, a dial wheel ratchet, said second gear train connecting said shaft and said dial wheel ratchet, means connecting said dial wheel ratchet to said second dial wheel, a plurality of cams slidably attached to said shaft, a lever carrying a pawl adapted to actuate a sec-

ond ratchet, means for selectively connecting any of said cams to said lever in actuating relationship dependent upon the predetermined size of the lot of counted articles, and means connected to said second ratchet for actuating the separating means.

7. In counting mechanism, the combination of a rotatable dial wheel for indicating the number of individual articles which have passed through a counting zone, a ratchet to operate the same, a plurality of cams operable with said ratchet, means for separating counted articles in lots of various sizes, each cam being operable individually to actuate the separating means thus separating counted articles in lots of predetermined size, a shaft, a yoke mounted on said shaft, and a handle disposed on said shaft, said shaft being rotatable to permit said yoke to dispose any of said cams in operable position.

8. In counting mechanism, the combination of a rotatable dial wheel for indicating the number of individual articles which have passed through a counting zone, a ratchet to operate the same, means for separating counted articles in lots of various sizes, a second rotatable dial wheel for registering multiples of the individual count, a gear train operable with said ratchet, a shaft, said gear train being connected to said shaft, a second gear train, a dial wheel ratchet, said second gear train connecting said shaft and said dial wheel ratchet, means connecting said dial wheel ratchet to said second dial wheel, a plurality of cams slidably attached to said shaft, a second ratchet, a lever carrying a pawl adapted to actuate said second ratchet, means connected to said second ratchet for actuating the separating means a second shaft, and a yoke mounted on said second shaft adapted to slide said cams on said first-mentioned shaft, said second shaft being rotatable to permit said yoke to dispose any of said cams in position to operate said separating means.

9. In a machine for counting and lot-segregating articles, the combination with means for conveying articles in single file through a counting zone, of a trigger disposed in said zone adapted to be actuated by movement of articles therethrough, a dial wheel for indicating the number of individual articles passing through said zone, means for rotating said dial wheel, an escapement serving to prevent rotation of said dial wheel, actuation of said trigger releasing the escapement thereby permitting rotation of said dial wheel a predetermined distance, a second dial wheel registering and visibly indicating multiples of the individual count, means connecting said second dial wheel to said first-mentioned dial wheel, a third dial wheel for registering and visibly indicating multiples of the individual count, and means connecting said third dial to said first-mentioned dial wheel; means for segregating counted articles in lots of predetermined size; means for actuating said segregating means; and a clutch for selectively operating said actuating means in accordance with the multiples wheel in use.

10. Counting mechanism comprising a dial wheel for indicating the number of individual articles passing through a counting zone, means to rotate said dial wheel, an escapement serving to prevent rotation of said dial wheel, a trigger, actuation of said trigger releasing said escapement to permit rotation of said dial wheel, a second dial wheel for registering and visibly

indicating multiples of the individual count; means connecting said second dial wheel to said first-mentioned dial wheel, a third dial wheel for registering and visibly indicating multiples of the individual count, means connecting said third dial wheel to said first-mentioned dial wheel, means for segregating counted articles in lots of predetermined size, means for actuating said segregating means, and a clutch for selectively operating said actuating means in accordance with the multiples wheel in use.

11. Counting mechanism comprising a dial wheel for indicating the number of individual articles passing through a counting zone, means to rotate said dial wheel, an escapement serving to prevent rotation of said dial wheel, a trigger, actuation of said trigger releasing said escapement to permit rotation of said dial wheel, a second dial wheel for registering and visibly indicating multiples of the individual count, a ratchet connected to said second dial wheel, a cam connected to said first dial wheel, a lever in engagement with said cam, a pawl secured to said lever adapted to rotate said ratchet, a third dial wheel for registering and visibly indicating multiples of the individual count, means connecting said third dial wheel to said first dial wheel, means for segregating counted articles in lots of predetermined size, means for actuating said segregating means, and a clutch for selectively operating said actuating means in accordance with the multiples wheel in use.

12. In counting mechanism, the combination of a rotatable dial wheel for indicating the number of individual articles which have passed through a counting zone, a ratchet to operate the same, a plurality of cams operable with said ratchet, means for separating counted articles in lots of various sizes, each cam being operable individually to actuate the separating means thus separating counted articles in lots of predetermined size, a shaft, and a yoke mounted on said shaft, said shaft being rotatable to permit said yoke to dispose any of said cams in operable position.

13. In a machine for counting and lot-segregating articles, the combination with means for holding articles securely and in single file while advancing them through a counting zone, of a trigger disposed in the counting zone adapted to be actuated by the forward movement of each of the articles, a rotatable dial wheel for indicating the number of individual articles passing through the counting zone, a ratchet rotatable to operate the same, an escapement connected to said trigger serving to prevent the rotation of said ratchet, actuation of said trigger releasing the escapement to permit rotation of said ratchet, a second rotatable dial wheel for indicating multiples of the individual count, a second rotatable ratchet to operate the same, and mechanism connecting said second ratchet to said first dial wheel to rotate said ratchet a predetermined distance for each rotation of said first dial wheel; means for separating counted articles in lots of predetermined size; and actuating means for said separating means connected to and operable with said second ratchet of the counting mechanism.

14. In a machine for counting and lot-segregating articles, the combination with means for holding horizontally disposed articles securely and in single file while advancing them through a counting zone, of a member disposed in the counting zone adapted to be actuated by the for-

ward movement of each of the articles; counting mechanism for counting the articles, said counting mechanism comprising a ratchet adapted to be rotated a predetermined distance upon movement of each article past said member, an escapement connected to said member serving to prevent rotation of said ratchet, said ratchet being rotatable by release of said escapement, actuation of said member releasing said escapement, a second ratchet rotatable a predetermined distance for each rotation of said first ratchet, mechanism connecting said ratchets; means for separating counted articles in lots of predetermined size; and actuating means for said separating means connected to and operable with 15 said second ratchet of the counting mechanism.

16. In a machine for counting and lot-segregating articles, the combination with means for holding horizontally disposed articles securely and in single file while advancing them through a counting zone, of a member disposed in the counting zone adapted to be actuated by the forward movement of each of the articles; counting mechanism for counting the articles, said counting mechanism comprising a ratchet adapted to be rotated a predetermined distance upon movement of each article past said member, an escapement connected to said member serving to prevent rotation of said ratchet, said escapement including a scape wheel and a pallet adapted to be pivoted by actuation of said member to release said wheel, release of said wheel permitting rotation of said ratchet, a second ratchet rotatable a predetermined distance for each rotation of said first ratchet, mechanism connecting said ratchets; means for separating counted articles in lots of predetermined size; and actuating means for said separating means connected to and operable with said second ratchet.

17. In a machine for counting and lot-segregating articles, the combination with means for holding horizontally disposed articles securely and in single file while advancing them through a counting zone, of a trigger disposed in the counting zone adapted to be actuated by the forward movement of each of the articles, a rotatable dial wheel for indicating the number of individual articles passing through the counting zone, a ratchet rotatable to operate the same, means for rotating said ratchet, an escapement connected to said trigger serving to prevent the rotation of said ratchet, actuation of said trigger releasing the escapement to permit rotation of said ratchet, a second rotatable dial wheel for indicating multiples of the individual count, a second rotatable ratchet to operate the same, mechanism connecting said second ratchet to said first dial wheel to rotate said ratchet a predetermined distance for each rotation of said first dial wheel; means for separating counted articles in lots of predetermined size; and actuating means for said separating means connected to and operable with said second ratchet of the counting mechanism.

18. In a machine for counting and lot-segregating articles, the combination with means for holding horizontally disposed articles securely and in single file while advancing them through a counting zone, of a trigger disposed in the counting zone adapted to be actuated by the forward movement of each of the articles, a rotatable dial wheel for indicating the number of individual articles passing through the counting zone, a ratchet rotatable to operate the same, an escapement connected to said trigger serving to

5 prevent the rotation of said ratchet, actuation of said trigger releasing the escapement to permit rotation of said ratchet, a second rotatable dial wheel for indicating multiples of the individual count, a second rotatable ratchet to operate the same, and mechanism connecting said second ratchet to said first dial wheel to rotate said ratchet a predetermined distance for each rotation of said first dial wheel; a chute down which the counted articles pass to a container, the lower portion of said chute being divided into two sections, a gate adapted to be rotated to close one of said sections thereby directing counted articles into the other section, and actuating means for said gate connected to and operable with said second ratchet of the counting mechanism.

19. In a counting mechanism for counting closures disposed in single file as they advance through a counting zone, the combination of a trigger disposed in the counting zone adapted to be actuated by movement of articles therethrough, a rod connecting said trigger to the pallet of an escapement, a dial wheel for indicating the number of individual articles passing through said zone, means for rotating said dial wheel, rotation of said wheel being prevented by said escapement, movement of said trigger pivoting said pallet to release the scape wheel of the escapement thus permitting rotation of said dial wheel, a second dial wheel for indicating multiples of the individual count, a ratchet connected to said second dial wheel, a cam connected to and mounted for rotation with said first-mentioned dial wheel, a lever held in engagement with said cam, and a pawl secured to said lever and adapted to rotate said ratchet thereby rotating said second dial wheel a predetermined distance.

20. In a counting mechanism for counting closures disposed in single file as they advance through a counting zone, the combination of a trigger disposed in the counting zone adapted to be actuated by movement of articles therethrough, a rod connecting said trigger to the pallet of an escapement, a dial wheel for indicating the number of individual articles passing through said zone, means for rotating said dial wheel, rotation of said wheel being prevented by said escapement, movement of said trigger pivoting said pallet to release the scape wheel of the escapement thus permitting rotation of said dial wheel, a second dial wheel for registering and visibly indicating multiples of the individual count, a ratchet connected to said second dial wheel, a cam connected to and mounted for rotation with said first-mentioned dial wheel, a lever held in engagement with said cam, and a pawl secured to said lever and adapted to rotate said ratchet thereby rotating said second dial wheel a predetermined distance, means for segregating counted articles in lots of predetermined size, and means operable with the ratchet of said counting mechanism for actuating said segregating means.

21. In a counting mechanism for counting closures disposed in single file as they advance through a counting zone, the combination of a member disposed in the counting zone adapted to be actuated by movement of articles therethrough, a dial wheel for indicating the number of individual articles of a predetermined lot which have passed through the counting zone, means for rotating said dial wheel, an escapement serving to prevent rotation of said dial wheel, actuation of said member releasing the escapement thereby permitting rotation of said dial wheel, a

second dial wheel for registering multiples of the individual count, a cam connected to said first-mentioned dial wheel, a ratchet connected to said second dial wheel, a lever engaging the surface of said cam, and a pawl secured to said lever and adapted to rotate said ratchet thereby rotat-
ing said second dial wheel a predetermined dis-
tance.

21. In a counting mechanism for counting clo-
sures disposed in single file as they advance 10 through a counting zone, the combination of a trigger disposed in the counting zone adapted to be actuated by the forward movement of each of the articles, a rotatable dial wheel for indicating the number of individual articles passing 15 through the counting zone, a ratchet rotatable to operate the same, means for rotating said ratchet, an escapement connected to said trigger serving to prevent the rotation of said ratchet, actuation of said trigger releasing the escape-
ment to permit rotation of said ratchet, a second 20 rotatable dial wheel for indicating multiples of the individual count, a second rotatable ratchet to operate the same, and mechanism connecting said second ratchet to said first dial wheel to 25 rotate said ratchet a predetermined distance for each rotation of said first dial wheel.
